UNITED STATES PATENT OFFICE.

JARED MARIS, OF COLUMBUS, OHIO.

DESIGN FOR THE ORNAMENTATION OF FLANGES FOR HUBS.

SPECIFICATION forming part of Design No. 16,430, dated December 29, 1885.

Application filed October 30, 1885. Serial No. 181,422. Term of patent 14 years.

To all whom it may concern:

Be it known that I, JARED MARIS, a citizen of the United States, residing at Columbus, in the county of Franklin and State of Ohio, have

5 invented and produced a new and original Design for Flanges or Bands for Wheel-Hubs, of which the following is a specification, reference being had to the accompanying drawing, forming part thereof.

10 My invention relates to a design for the ornamentation of the periphery and face of a hub flange or band; and it consists in the elongated facets or depressions on the outer face of the band or flange at periphery.

15 The accompanying drawing represents a flanged shell band embodying my design.

A represents a flange or band having the elongated facets or depressions b on the face of the flange or band, at the outer edge thereof.

20 These facets or depressions are of width sufficient to give to the periphery of band or flange a scalloped appearance.

I do not confine myself to the exact size of the several facets and depressions, but consider myself at liberty to vary their size whenever desired. 25

I do not claim, broadly, in this application, facets on the face of a hub-band, but reserve the right to claim the same in my pending application No. 180,554, filed September 12, 1885. 30

Having fully described my design, what I claim as new, and desire to secure by Letters Patent, is—

In a design for the shell band of a wheel-hub, the ornamentation of the same, consisting 35 in elongated facets or depressions in the face of the flange, at the periphery thereof, substantially as described and shown.

JARED MARIS.
